UNITED STATES PATENT OFFICE

155,714

DESIGN FOR A COMBINED STAND AND ELECTRIC FAN

Jacob W. Kisling, St. Louis County, Mo.

Application August 25, 1948, Serial No. 148,290

Term of patent 3½ years

(Cl. D26—7)

To all whom it may concern:

Be it known that I, Jacob W. Kisling, a citizen of the United States, residing in the county of St. Louis and State of Missouri, have invented a new, original, and ornamental Design for a Combined Stand and Electric Fan, of which the following is a specification, reference being had to the accompanying drawing, forming a part thereof.

In the drawing:

Fig. 1 is a top plan view of a combined stand and electric fan;

Fig. 2 is a side elevational view, and

Fig. 3 is a further side elevational view, taken

at a right angle to Fig. 2, each view showing a combined stand and electric fan of my new design.

I claim:

The ornamental design for a combined stand and electric fan, substantially as shown.

JACOB W. KISLING.
